JOHN HUGGETT AND JOHN ALBERT HUGGETT, OF EASTBOURNE,
ENGLAND.

Letters Patent No. 89,224, dated April 20, 1869; patented in England, September 27, 1867.

IMPROVED MACHINE FOR FORGING HORSE-SHOE NAILS.

The Schedule referred to in these Letters Patent and making part of the same

To all to whom it may concern:

Be it known that we, JOHN HUGGETT and JOHN ALBERT HUGGETT, of Eastbourne, in the county of Sussex, England, subjects of the Queen of Great Britain, have invented or discovered new and useful "Improvements in the Manufacture of Horse-Nails, and other nails, and in Machinery used therein;" and we, the said JOHN HUGGETT and JOHN ALBERT HUGGETT, do hereby declare the nature of the said invention, and in what manner the same is to be performed, to be particularly described and ascertained in and by the following statement thereof; that is to say:

This invention has for its object, improvements in the manufacture of horse-nails, and other nails, and in machinery used therein.

We employ a hammer, worked by power, by which a regular reciprocating motion is given to it.

On the face of the hammer are two dies, one corresponding in form to the side of the nail, and the other to its edge.

This hammer works upon an anvil, also having the incline or bevel of the nail formed upon it.

The bar of iron which is to be drawn down to form a nail, is received into a holder, which turns it one-quarter round, and shifts it sideways from one die of the hammer to the other, after each blow, so that the bar may be alternately struck on the side and edge, and alternately by one and the other of the dies which the hammer carries.

The holder for the bar to be drawn down may conveniently be an axis connected with the hammer, so that it turns one-quarter round between each stroke, first one way, then the other.

And in order that our said invention may be most fully understood and readily carried into effect, we will proceed to describe the drawings hereunto annexed.

Description of the Drawings.

Figure 1 is a side view of the apparatus which we employ;

Figure 2 is an end view; and

Figure 3 is a plan, partly in section, of the same.

a is the frame of the machine.

It has upon it a standard, *a'*, carrying the main axis, *b*, on which there are fast-and-loose pulleys, *b'*, to receive a driving-belt.

b is an eccentric on this axis, receiving an eccentric rod, *c*, which, at its other end, is jointed to the spring-arm *d*.

This arm *d*, at one end, pivots upon a spring-standard, *a'*, fixed to the frame *a*.

At its other end, the spring-arm *d* is jointed to a cylindrical hammer-head, *e*, which is capable of rising and falling within a corresponding cylindrical guide, *a''*, forming part of the standard *a'*.

At the upper end of the hammer-head *e*, a piston is

formed, which works in a corresponding cylinder at the top of the standard *a'*, and the space enclosed under this piston communicates with an air-passage fitted with a valve, which is worked by the descending-rod *f*.

All these parts are not shown in any great detail in the drawings, because they are not, in themselves, new, and they form no part of the present invention.

Their action is as follows:

As the axis *b* revolves, the eccentric *b* gives a vibrating motion to the spring-arm *d*, and the hammer-head *e* is thus worked up and down in its guide, striking a blow upon the anvil *g* at each reciprocation, and during this time air is alternately received into and expelled from the space underneath the piston, upon the hammer-head.

When it is desired to prevent the hammer striking upon the anvil, the air-valve, which allows the ingress and egress of air, as above explained, is closed, and the air being trapped underneath the piston, prevents the descent of the hammer-head, the spring-arm *d* and the spring-standard *a'* then bending under the action of the eccentric *b*.

The anvil *g* has set into it two steel dies, *g'* and *g''*, which are shown separately in the Figures 4 and the Figures 5 respectively, and also in Figure 6, which is a side view of the hammer-head and anvil.

One of the dies *g'* *g''* has upon it an incline or taper corresponding with the face of the nail, and the other an incline or taper corresponding with the side of the nail.

The hammer-head also carries two steel dies, corresponding in form to the dies *g'* *g''*, and working with them respectively.

h *h'* are two blocks, bolted to the table of the frame *a*, and holding, in a recess between them, the axis *k*, which has a rectangular notch, *k'*, formed in it, from end to end; and into this notch the nail-rod is received, and it is locked in a clip, *k''*, at the front end of the axis, by the locking-screw *k'''*.

k' *k''* are pulleys on the axis *k*.

Around them two cords pass, one to a spring, *l*, tending constantly to keep the axis *k* with the notch *k'* uppermost in the position in which it is represented in the drawing, and with a projection at *k'''* upon it, resting against a stop on the block *h*, whilst the other cord passes to a lever, *m*, having a spring, *n*, attached to it, and this spring *n*, when free to act, overpowers the spring *l*, turning the axis *k* to the right hand.

m' is a truck of the lever *m*, which the spring *n*, when the machine is at work, keeps in contact with the cam *o*.

The axis of this cam is driven by a spur-wheel, *o'*, upon it, gearing with a pinion, *p*, of half the size, upon the axis *b*. Thus it will be seen that the action of the cam *o* is to partially rotate the axis *k* first one way and then the other, between the successive blows of the hammer, and the parts are so adjusted that the axis *k*

may make a quarter rotation. This partial rotation carries the nail-bar from one pair of dies of the anvil and hammer to the other, and, at the same time, it turns the bar or quarter round between the blows, and in this way the rod is pointed.

The pointed bar is removed from the machine, and the pointed end being shorn off, forms the nail required.

p is a treadle, connected by a link with the lever q , which springs q' tend constantly to draw to its highest position, or that in which the drawing represents it; and this position it occupies when the action of the machine is stopped.

At this time it will be seen that a rod, r , jointed to the end of the lever q , supports the pin m' on the lever m , and prevents the spring n acting through the lever and cord on the axis k , which consequently remains stationary. But when the treadle p and lever q are depressed, the rod r is also carried down until the incline at its upper end comes opposite the pin m' , and the lever m and spring are free to operate.

When the treadle p is depressed, the arm q'' , on the axis of the lever q , by means of the rod f , opens the valve, and admits air to and from the cylinder a'' , so as to allow the hammer to operate.

The lever q , when drawn down by the treadle, gives motion to the claw s , and in descending, the upper portion of said claw comes in contact with the screw k'' , and turns it, so as to tighten it upon the properly-heated bar, which has been put into the notch in the axis k , and so the bar is held whilst it is being forged.

Similarly, when the lever q rises, the lower portion of the claw s , at the proper time, comes in contact with the screw k'' , and partly turns it in the opposite direction, and the nail-rod is released, so that it may be removed from the machine, and another substituted.

The clip k' is able to move a short distance longitudinally, in relation to the axis k , which carries it so that the nail-bar may be more free to draw out, or lengthen under the blows of the hammer.

Two studs, k'' k''' , fixed in the end of the axis, support and serve as guides for the clip-piece k' , and springs upon these studs press it toward the axis. These springs, however, yield somewhat to the lengthening of the nail-rod under the hammer.

t is a support, to guide the workman in placing the nail-bars in the machine.

w is a pusher, connected with the lever q , which, when the lever q is allowed to rise to stop the forging of the nail-bar, acts on a projection upon the clip k' , so as, if necessary to turn it and the axis k into a position suitable to admit of the removal of the forged nail-rod, and the introduction of a fresh rod into the machine.

The nail-bar, when it is inserted into the machine, is made to touch at its end the gauge v .

This gauge turns on a centre at v' . It is drawn forward into a position for use by the spring v' , and it is thrust back out of the way of the hammer, when the treadle p is depressed by the inclined end of the rod v , which is jointed to the arm q'' , on the axis of the lever q .

w' is a catch-lever, to hold the lever q when depressed. The lever is freed when desired, by placing the foot on a treadle-arm formed in connection with the catch-lever.

z is a hand-lever, giving motion to a wedge-piece, z' , the face of which forms a portion of the anvil-surface. It is used to point the nail when the forging is complete.

The wedge is then drawn forward, up to the stop z'' , by the hand-lever, so as to raise the surface on which the point rests, so that it alone may receive a finishing or pointing-blow. A spring causes the return of the hand-lever z .

y is a pipe, by which air is blown upon the anvil, to clear away scale.

Having thus described the nature of our said invention, and the manner of performing the same, we would have it understood that we do not confine ourselves to the exact details described.

1. We claim the combination of the screw k'' , or other equivalent device, with the claw s and lever q , for automatically holding and releasing the nail-bar in the notch of the holder k , substantially as before described.

2. We claim, in combination with a reciprocating and turning holder, a hammer faced with two dies for forming the sides and taper of the nail, and the anvil, faced with two corresponding dies, substantially as before set forth.

3. We claim the device consisting of the gauge v , spring v' , rod v'' , arm q'' , and lever q , all arranged and operating substantially as before described.

4. We also claim the device consisting of the cords and springs attached to the axis k , the cam o , the lever m , springs l n , and gearing b' and c' , for shifting the holder k , substantially as before described.

5. We also claim, in combination with the above device, the rods r and w , and the lever q , for returning the holder k to the position for receiving the blank, all substantially as hereinbefore described.

JOHN HUGGETT.

JOHN ALBERT HUGGETT.
